RUFUS WRIGHT, OF BROOKLYN, NEW YORK.

Letters Patent No. 74,187, dated February 4, 1868.

IMPROVED CHERRY-STONER.

The Schedule referred to in these Letters Patent and making part of the same.

TO ALL WHOM IT MAY CONCERN:

Be it known that I, RUFUS WRIGHT, of Brooklyn, in the county of Kings and State of New York, have invented a new and improved Cherry-Stoner; and I do hereby declare that the following is a full, clear, and exact description thereof, which will enable those skilled in the art to make and use the same, reference being had to the accompanying drawings, forming part of this specification.

This invention relates to a new and improved machine for depriving cherries of their pits or stones; and it consists of a peculiar construction and arrangement of parts, as hereinafter fully shown and described, whereby the work may be done with great rapidity and in a perfect manner. In the accompanying sheet of drawings—

Figure 1 is a front view of my invention, a portion being in section, as indicated by the line *z z*, fig. 2.

Figure 2, a side view of the same.

Figure 3, a horizontal section of the same, taken in the line *y y*, fig. 2.

Similar letters of reference indicate corresponding parts.

A represents a standard attached to a suitable base, *B*, and having a horizontal shaft, *C*, fitted in suitable bearings, *a a*, on its upper end. One end of this shaft *C* is provided with a pinion, *D*, with which a wheel, *E*, on a driving-shaft, *F*, gears. On the opposite end of the shaft *C* there is a double cam, *G*, which also serves the purpose of a crank to operate a vertical reciprocating rod, *H*, which is fitted in a guide, *b*, attached to the standard, said rod *H* being connected to the cam by a rod, *I*, as shown clearly in fig. 1. In the lower end of the rod *H* there is secured a series of small rods or needles, *c*, five, more or less, being used, and provided near their lower ends with notches or barbs, the use of which will be presently shown. *J* is a hopper attached to one side of the standard *A*, and having a tube, *K*, extending down from it. This tube has a bottom, *L*, made separately from it, and attached to the lower end of a vertical rod, *M*, which is fitted in suitable bearings, *d*, secured to the exterior of the tube, as shown in fig. 1, the rod *M* being allowed to turn freely in its bearings. The bottom, *L*, is provided with a curved projection, *N*, and is hollowed at one edge or side, as shown clearly in fig. 3. *O* is a spring attached to the standard *A*, and connected to the bottom *L*. This spring has a tendency to keep the bottom underneath the tube *K*. The upper end of the rod *M* has a crank, *P*, formed on it, against which a rib, *e*, on side of the cam *G*, acts to throw the bottom *L* out from underneath the tube *K*, the spring *O* throwing it back underneath the tube *K* after the rib *e* has passed the crank. *Q* represents a horizontal bed, which extends out from the standard *A*, and has a curved guard, *R*, attached to its upper surface, and a hole, *f*, made through it, a circular cavity, *g*, being made in the upper surface of the bed, concentric with the hole *f* and the guard *R*. Underneath the bed *Q* there is a horizontal arm, *S*, formed by bending the lower end of a vertical rod, *T*, in a horizontal position. This rod *T* is fitted in suitable bearings, *h*, and its upper end is provided with a crank, *i*, against which a pin, *j*, on the cam *G*, acts, said crank having a spring, *k*, bearing against it, to throw it back each time after the pin *j* has acted upon it. *U* is a bar, which is fitted loosely on a journal, *l*, attached to the standard *A*, and passes through a fork, *m*, at one end of a spring, *V*, attached to the standard *A*. The lower end of the bar *U* is provided with two plates, *u u*, shown clearly in fig. 1, the space between said plates being sufficiently large to receive a cherry. The cam *G* acts against the other end of the bar *U*, to move it in one direction, while the spring *V* moves it in the opposite direction.

The operation is as follows: The hopper *J* is supplied with cherries, which pass down into the tube *K*, and rest upon the bottom *L*. The shaft *F* is rotated through the medium of a crank. The rib *e* of the cam *G*, in acting against the crank *P*, turns the bottom *L* out from underneath the tube *K*, and the cherries drop down, one at a time, on the bed *Q*. When the rib *e* passes the crank *P*, the spring *O* turns the bottom *L* underneath the tube *K*, and the projection *N* of the bottom throws the cherry into the cavity *g* of the bed *Q*, the guard *R* serving to prevent the cherry being thrown or cast from the bed. At this juncture the rod *H* is forced down by the cam, and the needles *c* penetrate the cherry and drive out the pit or stone, forcing it through the hole *f* in the bed *Q*, and the horizontal arm *S*, by the action of the pin *j* of the cam *G* against the crank *i* of rod *T*, is thrown across the under side of the hole *f*, and detaches the pit or stone from the cherry. The rod *H* then rises, the notches or barbs on the rods causing the cherry to adhere to it, the cherry being stripped off as it comes in contact with the upper plate *u* of the bar *U*, and, passing between the two plates *u u*, is discharged from the machine by a sudden forward movement of the lower end of said bar.

The device performs its work rapidly and in a perfect manner.
I claim as new, and desire to secure by Letters Patent—

1. The reciprocating rod H, armed with the needles e, provided with notches or barbs, in connection with the bed Q, having the recess or cavity g made in it, and the hole f extending entirely through it, with the arm S working underneath the hole f in the bed, all arranged substantially as and for the purpose set forth.
2. The vibrating-bar U, provided with the plates u u, in combination with the reciprocating rod H, armed with the needles e, and the bed Q provided with the hole f, all arranged substantially in the manner as and for the purpose specified.
3. The vibrating bottom L, in connection with the tube K, the former being provided with the curved projection N, and arranged to operate in connection with the bed Q and guard R, all arranged to operate substantially as and for the purpose set forth.
4. The cam G, provided with the rim e and pin j, and connected with or arranged to operate the rod H, bottom L, strike or arm S, and the bar U, for the purpose specified.

RUFUS WRIGHT.
